CLOSURE OPERATING MECHANISM

James E. Bancroft, Detroit, Mich., assignor, by
mesne assignments, to The Peelle Company,
New York, N. Y., a corporation of New York

Application March 14, 1928. Serial No. 261,572

7 Claims. (Cl. 268—59)

This invention relates to closure operating mechanism and more particularly to a power driven apparatus arranged to open and close a door.

5 Sliding doors are often used in connection with freight elevator shafts, and these doors have to be opened and closed a great many times during the course of a day. It is important that the door at each floor move as rapidly as possible so as to 10 avoid any unnecessary delay in the operation of the elevator, and that the door start and stop easily and gradually to avoid undesirable noise and an extraordinary amount of expense for maintenance. It is also desirable that the 15 mechanism be readily adjustable so that a standard equipment may be utilized for various sizes and types of doors and motors and in all sorts of locations. A further desirable feature involves the use of a motor which may run 20 through a given travel cycle and automatically limit its own operation in such a manner as to stop when the door is in a fully open or a fully closed position; and adjustments should be provided which permit the final positions of the door 25 to be changed without affecting the automatic mechanism which controls and limits the motor travel.

The main object of my invention is accordingly to provide a simple form of door operating mechanism embodying such desirable features which is capable of being cheaply manufactured and readily installed and is adapted for use with various types of doors and will give dependable 30 service.

35 With this and other objects in view, as will be apparent to one skilled in the art, my invention resides in the combination of parts set forth in the specification and covered by the claims appended hereto.

40 Referring to the drawings illustrating one embodiment of my invention and in which like reference numerals indicate like parts:

45 Fig. 1 is an elevation of my apparatus connected to a pair of vertically slideable counterbalanced doors, the doors being shown in the closed position, and parts being broken away for 50 clearness of illustration;

Fig. 2 is a plan view of the parts shown in Fig. 1;

55 Fig. 3 is a plan view similar to Fig. 2, but with the parts in the position they will assume when the doors are open;

Fig. 4 is an enlarged perspective view of one 60 end of the sliding bar.

Fig. 5 is an enlarged perspective view of one of the guide bearings for the sliding bar;

Fig. 6 is an enlarged elevation of the braking mechanism for the motor;

Fig. 7 is a detail showing the construction of 30 the limit switch, together with a diagram of the electric wiring connections thereto; and

Fig. 8 is a perspective view of the worm gear reduction unit and limit switch with parts broken 45 away for clearness of illustration.

While the invention is applicable to a single 50 door, and to doors of various types, I have illustrated one embodiment as applied to a pair of vertically slideable counter-balanced doors of the type frequently used in connection with freight 55 elevator shafts. The upper door 10 and the lower door 11 may be arranged to slide vertically in suitable guides, not shown, behind a rectangular opening 13 in a vertical wall 14. This wall may form a portion of an elevator shaft or hatchway. 60 In accordance with the usual construction the doors 10 and 11 are connected by means of flexible members, such as the chains 16 which pass over sprocket wheels 17 rotatably mounted on the inside of the wall. By this means each door serves 65 as a counterweight for the other, and the only resistance to be overcome in operating the doors is that due to inertia and friction. Doors of this 70 type are frequently operated by hand, it being 75 merely necessary to grasp one door and move it to the desired position, thereby causing the other door to move also. However, such doors are 80 ordinarily of very heavy construction and operation by hand is undesirably slow and laborious. 85

In order to operate the doors by power I provide 90 suitable connections, such as shafts 19 and 20, which are keyed to the sprockets 17 and extend entirely through the wall 14 to the outside thereof. Various methods of driving these shafts 95 may be utilized within the scope of my invention, but I prefer to mount sprockets 22 and 23 on their outer ends, and to provide a suitable chain 25 for these outer sprockets. In order to reduce 100 the cost and simplify the construction the intermediate portion of the chain, which does not pass over the sprockets during operation, may be replaced by a rigid rod 26. While it is possible to so mount the doors that the sprockets 22 and 23 will both turn in the same direction, 105 the ordinary construction is that shown in the drawings in which it is apparent that sprockets 22 and 23 turn in opposite directions. With this arrangement it is necessary for the chain 25 to 110 pass around the sprocket 22 in one direction and

around sprocket 23 in the other direction, as shown clearly in Fig. 1.

The doors 10 and 11 are operated by a suitable source of power, such as electric motor 30, 5 which may be conveniently mounted upon a base 31 attached to the wall 14, above the opening 13. While this motor may be of any suitable type, I prefer to use a motor which is easily reversible, and I have found a three phase induction motor satisfactory when the proper electric current is available.

In order to reduce the load upon the driving motor and to avoid all shock and slamming of the doors during operation, I so connect the 15 motor to the chain 25 as to give it, as well as the doors connected thereto, a substantially simple harmonic motion. As is well known, a simple harmonic motion is the motion of the projection on a straight line of a point moving at a uniform 20 velocity in a circular path. While various mechanical devices may be utilized for this connection, I prefer to arrange a crank which will be on its dead center position when the door is either fully open or fully closed. While a crank, 25 due to so-called "angularity", does not give a theoretically exact simple harmonic motion, nevertheless, it is sufficiently near to the theoretical for all practical purposes, and it has various advantages over other constructions. As illustrated, 30 I provide a crank 33 which is rotatable about a vertical axis, although it is apparent it may be arranged for rotation about a horizontal axis if it is desired. The crank 33 is arranged to be rotated by the motor 30 through a suitable speed reduction device, and for this purpose I mount the crank on the shaft 34 (Fig. 8) of a worm gear 35 which is driven by a worm 37 directly connected to the motor. The worm and worm gear are preferably enclosed in a suitable casing 38, mounted upon the bracket 31.

In order to form a suitable connection between the crank 33 and the chain 25, I provide a bar 40, shown substantially square in cross section, which is arranged to slide in a pair of guides 41 mounted upon the wall 14. Each guide 41, 45 as shown in Fig. 5, is provided with a slot 42 of the proper size and shape to fit the bar 40. Each end of the bar 40 is connected to one end of the chain 25, and for this purpose one end of the bar is provided with a downwardly projecting portion 44, illustrated in detail in Fig. 4. This projection 44 has an opening 45 therethrough of sufficient size to permit the chain 25 and the rod 26 to pass freely therethrough. 50 The motion of the crank 33 is transmitted to the bar 40 by means of a connecting rod 47 which is pivoted to the crank at 48 and to the bar at 49. As shown in Figs. 2 and 3 the parts are so constructed and arranged that the crank 55 33 is on dead center, that is, in line with the connecting rod, when the doors are fully open or fully closed.

While the ratio between the different sprockets may be varied to accommodate the door operating mechanism to doors having different amounts of travel, I prefer to provide means for varying the effective length of the crank arm 33, thereby permitting an adjustment of the door travel which may be made easily in the field. For this purpose the crank 33 may comprise two relatively adjustable parts such as the extension 51 and the arm 52 (Fig. 8). These parts may be held together by means of screws 54 passing through slots 55 in the extension 51. 60 It will be apparent that the throw or effective

length of the crank may be varied by sliding the extension 51 relative to the arm 52 and clamping it in its new position by means of the screws 54.

Various electrical devices and connections may be utilized within the scope of my invention for controlling the electric motor to open and close the doors. I have illustrated diagrammatically in Fig. 7 one simple arrangement of apparatus for this purpose. As shown, the motor 30 is connected to a suitable source of three phase alternating current 60 through a magnetically operated reversing switch 61 having magnet coils 62 and 63. This switch 61, which is of a type well-known in the art, is so arranged that when coil 62 is energized the switch will be thrown so as to operate the motor 30 in one direction and when the coil 63 is energized it will be thrown to operate the motor in the opposite direction. When neither coil is energized the switch will be open and the motor circuit broken. Push buttons 65 and 66 are provided for opening and closing the doors respectively. A suitable limit switch 68 is provided for the purpose of automatically breaking the motor circuit when the doors reach either of their extreme positions. The limit switch 68 comprises a central stationary contact member 69 with movable contact members 71 and 72 at each side thereof. Contacts 71 and 72 are mounted upon pivoted arms 74 and 75 respectively. Springs 77 and 78 tend to hold contacts 71 and 72 against the central contact 69. The central contact member 69 is connected by a suitable electric conductor with one of the main power wires and the movable contacts 71 and 72 are connected with another of the main power wires through coil 63 and push button 66 and coil 62 and push button 65 respectively. 100

As shown in Fig. 8, the limit switch 68 may be mounted adjacent to the worm gear casing 38 and arranged to be operated by the movement of the crank 33. For this purpose an arm 90 is pivotally attached to the casing 38 by means of a vertical stud 91. This arm 90 has at its outer end an enlarged portion 93 located between the arms 74 and 75. At its inner end the arm 90 carries a pivotally mounted cam roller 94. Suitable cam members 96 and 97 are adjustably mounted by means of screws 98 on a horizontal disk 100 integral with the crank 33. These parts 110 are so arranged that as the doors approach either one of their extreme positions one of the cam members 96 and 97 will contact with the roller and move the arm 90 about the stud 91, thereby causing one of the contact members 71 and 72 120 to be moved away from the central contact 69.

In order to insure the stopping of the motor 30 as soon as the current supplied thereto is interrupted, I prefer to provide the braking device illustrated in Fig. 6. This comprises a pair of 130 brake shoes 106 mounted upon vertical arms 107 which are pivoted at their lower ends. A tension spring 109 connects the arms at their upper ends and normally holds the brake shoes in contact with a pulley 110 mounted upon the 140 motor shaft. In order to hold the shoes 106 out of contact with the pulley during the period when the motor is supplied with electric power, I provide an electro-magnetic coil 115 which is connected across two of the motor terminals. 145 This coil 115 is arranged when energized to attract an armature 116 mounted upon the pivoted lever 118. The lever 118 is connected by a vertical link 119 with the toggle arms 121 which are pivoted to the upper ends of the arms 107. 150

- It is apparent that when the armature 116 is attracted by the coil 115 it will result in forcing the upper ends of the arms 107 apart against the action of the spring 109 and thereby remove 5 the brake shoes from the pulley 110 and permit the motor to rotate freely. As soon as the motor current is interrupted the coil 115 will be de-energized and the spring 109 will pull the shoes 106 into contact with the pulley 110 and bring 10 the motor to an immediate stop. Since the velocity of the doors when they reach either extreme position is zero, as a result of the simple harmonic motion, the brake has only the momentum of the motor armature to overcome. 15 Hence a relatively small brake can be used, as compared with prior constructions in which the brake must stop the doors in addition to the motor.
- The operation of my apparatus will now be 20 apparent from the above disclosure. Suppose the doors are originally in the closed position, as shown in Fig. 1. To open them it is merely necessary to press the push button 65. This will permit the current to flow through the coil 62, contact 72, and contact 69. This will throw the magnetic switch 61 so as to operate the motor 30 and rotate the crank 33 in the direction of the arrow in Fig. 2. Since the crank arm 33 is originally on dead center it is apparent that a very 25 small starting torque will be required of the motor in starting the doors. As the crank 33 rotates the doors will gradually reach a high rate of speed and then gradually slow down to a smooth stop without any shock or slamming. As the 30 doors approach their fully open position the cam 97 will contact with the roller 94 and cause the arm 90 to swing about its pivot and thereby lift the contact member 72 away from the contact 35 69. This breaks the circuit through the coil 62 and the magnetic switch 61 will then return to neutral position and break the main motor circuit, thereby stopping the motor. To close the doors, it is merely necessary to operate the push 40 button 66 whereupon current will flow through the coil 63 and the contacts 71 and 69 so as to throw the switch 61 and cause the motor to operate and rotate the crank 33 in the direction of the arrow in Fig. 3. As the doors approach their 45 fully closed position the cam 96 will strike the cam roller 94, thereby swinging the arm 90 and lifting contact 71 away from contact 69, thus 50 stopping the door. With my apparatus it is possible to use a motor of a small size and yet operate the doors very rapidly without overloading the motor or causing any shock or damage to the 55 doors. The apparatus is easily installed, quiet in operation and requires a minimum of attention.
- Having thus described my invention, what I claim as new and desire to secure by Letters 60 Patent is:—
1. A closure operating mechanism for a slideable door comprising a driving wheel, a flexible power transmission connection between said wheel and door to operate the same, a driving motor, and connections between said motor and wheel arranged to give the door a substantially simple harmonic motion as it moves from one extreme position to the other.
  2. A closure operating mechanism for a slideable door comprising a driving wheel, a flexible power transmission member passing over said wheel and driven thereby, connections between said member and the door, an electric motor, a crank arm driven by said motor, and means connecting the crank arm to the wheel to rotate the latter in either direction and thereby operate the door. 80
  3. A closure operating mechanism for a slideable door comprising a driving wheel, a flexible power transmission member driven by said wheel and connected to move the door to an open or a closed position, a driving chain connected with said wheel, a motor, a crank connection between the motor and the driving chain, and means for limiting the extent of travel of the door in either direction. 85
  4. An operating mechanism for a slideable door comprising a driving wheel, a flexible power transmission connection between said wheel and door to open and close the same, a driving motor, a crank driven thereby, and connections including a connecting rod between said crank and wheel to rotate the same, said parts being so constructed and arranged that the crank will start and stop substantially on a dead center 100 when the door is in the open and closed position. 95
  5. A closure comprising a slideable door, a driving wheel, a flexible power transmission member connecting said wheel with the door, a shaft connected to said driving wheel, a sprocket wheel mounted on the shaft, a chain passing over the sprocket wheel, a slideable bar connected to the chain, a motor driven crank, and a connecting rod pivoted at one end to the crank and at the other 105 end to the slideable bar. 110
  6. A closure comprising a vertically slideable door, a rotatable driving wheel at each end of the door, a flexible power transmission member passing over each wheel and connected to the 115 door in such a manner that rotation of the two wheels in opposite directions will slide the door in one direction, a shaft connected to each wheel, a sprocket mounted on each shaft, a chain which passes around one sprocket in one direction and the other sprocket in the other direction, a slideable bar connected to each end of said chain, and a power operated mechanism connected to slide said bar. 120
  7. A closure comprising a slideable door arranged to move to an open or closed position, an electric motor, a crank arm driven by the motor, a connecting rod driven by the crank arm and arranged to slide the door, said parts being so constructed and arranged that the crank arm 125 will be substantially on one dead center when the door is in a fully open position and substantially on the other dead center when the door is in a fully closed position, means including a limit switch arranged to interrupt the electric current supply to the motor when the door reaches such open or closed position, and an electro-magnetic brake arranged to stop rotation of the motor upon interruption of said current supply. 130
